UNITED STATES PATENT OFFICE.

ARTHUR MARRS, OF VICKSBURG, MISSISSIPPI, ASSIGNOR OF ONE-THIRD
TO S. P. BOLIAN AND ONE-THIRD TO DAVID A. GRAHAM, OF VICKS-
BURG, MISSISSIPPI.

TRAIN-LINE-WHISTLE REDUCING-VALVE.

No. 800,751.

Specification of Letters Patent.

Patented Oct. 3, 1905.

Application filed January 31, 1905. Serial No. 243,508.

To all whom it may concern:

Be it known that I, ARTHUR MARRS, a citizen of the United States, residing at Vicksburg, in the county of Warren and State of Mississippi, have invented a new and useful Train-Line-Whistle Reducing-Valve, of which the following is a specification.

The invention relates to a train-line-whistle reducing-valve.

10 The object of the present invention is to improve the construction of the signaling equipment of a train and to provide a simple, efficient, and reliable train-line-whistle reducing-valve designed, primarily, for use on 15 freight-trains, where there is only a train-line pipe and no signal-line, and adapted to enable the conductor of a freight-train to signal the engineer by a reduction of the pressure in the train-line pipe without affecting the triple 20 valves of the brake equipment.

The invention also has for its object to simplify and lessen the cost of the signal equipment of passenger-trains by dispensing with the signal-line on all the cars and to enable 25 the train-line pipe of the brake equipment to serve for operating both the whistle-signal and the air-brakes.

Another object of the invention is to provide a train-line-whistle reducing-valve adapted, when the engineer's brake-valve is operated, to cut out the signal and capable of automatically returning to its initial position when the train-line pipe is recharged and the 30 brake-valve is in a running position.

35 With these and other objects in view the invention consists in the construction and novel combination and arrangement of parts hereinafter fully described, illustrated in the accompanying drawings, and pointed out in 40 the claims hereto appended, it being understood that various changes in the form, proportion, size, and minor details of construction within the scope of the claims may be resorted to without departing from the spirit 45 or sacrificing any of the advantages of the invention.

In the drawings, Figure 1 is a side elevation of a locomotive provided with a train-line-whistle reducing-valve constructed in accordance with this invention. Fig. 2 is an enlarged sectional view of the train-line-whistle reducing-valve, and the whistle-signal valve, illustrating the arrangement of the

parts for operating the brakes. Fig. 3 is a similar view showing the running position 55 of the train-line-whistle reducing-valve. Fig. 4 is a vertical sectional view of a portion of a valve-casing. Fig. 5 is a reverse plan view of the lower end of the valve-casing. Fig. 6 is an enlarged detail sectional view illustrating the construction and arrangement of the upper check-valve. Fig. 7 is a horizontal sectional view illustrating the construction of the main valve and the manner of guiding the same. 60

65 Like numerals of reference designate corresponding parts in all the figures of the drawings.

1 designates a train-line-whistle reducing-valve designed to be located within the cab of 70 a locomotive and connected at its upper end to the bottom of the engineer's brake-valve 2 and at its lower end to the train-line pipe 3 of an ordinary brake equipment, such as is commonly used on freight-trains, where there 75 is only a train-line pipe and no signal-line pipe. The train-line-whistle reducing-valve is connected at intermediate points, as herein-after explained, with a whistle-signal valve 4, and the latter is connected in the ordinary 80 manner with a signal-whistle 5 of the usual construction. The engineer's brake and equalizing discharge-valve is connected with the main air drum or reservoir and performs its usual functions in controlling the air-brake 85 equipment. The casing of the train-line-whistle reducing-valve is provided with a cylinder 6, in which operates a piston 7, and connected with the stem 8 thereof at an intermediate point is a main valve 9. The 90 train-line-whistle valve, which is shown in a vertical position in the accompanying drawings, may be arranged in any other desired manner, as will be readily understood, and it is provided with passages 10 and 11, extending longitudinally of a lateral enlargement 12, which is located at one side of the cylinder. The lower ends of the passages communicate with the cylinder below the head of the piston through a transverse branch passage or 100 chamber 13. The passage 10, which is located between the passage 11 and the interior of the cylinder, terminates short of the upper end of the outer passage 11 and is connected at its upper end by a lateral branch 14 with 105 the cylinder. The upper end of the outer

passage 11 is connected by a lateral branch or chamber 13 with the cylinder or body portion of the valve-casing, and this chamber or passage, which is located above the piston and 5 beyond the stroke of the same, receives an upwardly-opening check-valve 16, arranged on a valve-seat 17 and normally held in a closed position by means of a coiled spring 18. The check-valve 16 is provided with a 10 stem which slides in a tubular screw 19. The screw 19, which has a polygonal wrench-receiving head, extends through a threaded opening of the top wall of the lateral branch passage or chamber 13 and terminates short of 15 the bottom thereof. The coiled spring is disposed on the valve-stem and on the screw which guides the valve in its movements.

The lower lateral branch passage or chamber 13 receives a downwardly-opening valve 20, arranged to engage a seat 21 at the lower 20 end of the longitudinal portion of the passage 10 and at the top wall of the lateral branch passage or chamber 13. The check-valve 20, which is smaller than the valve 16, is constructed in the same manner, being guided by 25 a tubular screw 22 and engaged by a coiled spring 23. The tubular screw is arranged in a threaded opening of the bottom wall of the lateral branch or chamber 13, and the coiled 30 spring is disposed on the valve-stem and on the inwardly-projecting portion of the screw 22. When air from the brake-valve enters the upper end of the valve-casing, it forces the piston down to a point below the lateral branch 35 14, as illustrated in Fig. 3 of the drawings, and the train-line pipe 3 and the whistle-signal valve 4 are charged, the air passing through the port or passage 10, which constitutes a feed-passage. The lower check-valve 20 opens 40 under such pressure and permits the air to pass into the cylinder beneath the piston-head.

The main valve 9 is provided with lateral and longitudinal ports or passages 24 and 45 25, communicating with each other. The lateral passage 24 is arranged at the upper end of the valve and extends from the center of the valve to one side thereof. The longitudinal port or passage 25 extends from the lateral 50 port or passage to the lower end of the main valve 9. The valve 9 is provided with a longitudinal slot or groove 27, which receives the piston rod or stem 8, and which is also engaged by a pin 26 for guiding the 55 valve and for maintaining the same in proper position. The pin, which has a threaded portion, is mounted in a threaded opening of one side of the cylinder, and it has an exteriorly-arranged head. The lateral port 24 of the 60 valve extends inwardly to the slot or groove 27 of the main valve. The main valve, which is cut away at opposite sides to provide passages 27^a, is provided at the outer end of the lateral port or passage 24 with a curved face 65 to fit the adjacent portion of the cylinder 6.

The whistle-signal valve 4 is of the ordinary construction, with the exception, in addition to being connected with the train-line-whistle reducing-valve at the usual upper passage 28, it is also provided with a lower exhaust-passage 29, which communicates with the space or chamber beneath the diaphragm 30. The upper passage is connected by a pipe or tube 31 with a nipple 32 of the cylinder, which is provided thereat with a port 33. 70 The lower exhaust-passage 29 is connected by a lower pipe or tube 34 with a nipple 35, located at a lower lateral port 36 of the cylinder. The whistle-signal valve is charged in the usual manner by air entering the top of 75 the whistle-valve when the valve 9 is in its normal or running position, as illustrated in Fig. 3 of the drawings. In this position the valve 9 closes the lower lateral or exhaust port 36, and the upper lateral port 33 is in communication with the space above the diaphragm 30 and with the train-line pipe. When it is desired to signal the engineer, a slight reduction is made in the pressure in the train-line pipe by operating a conductor's valve, 80 which may be arranged at any desired point on a train. The slight reduction in the train-line pipe does not affect the triple valves, but siphons the pressure from the space above the diaphragm 30 of the whistle-signal valve. The 85 pressure being greater below the diaphragm opens the valve, and the whistle is blown in the usual manner until the pressure within the whistle-signal valve becomes equalized. In a few seconds the whistle-signal valve will 90 be recharged and may be again operated. When the engineer's valve is operated to apply the brakes, the pressure in the cylinder above the piston is reduced, and the greater pressure below the piston moves the latter upward from the position shown in Fig. 3 to 95 that illustrated in Fig. 2. This movement of the piston closes the feed-port 14 and covers the upper lateral port 33 and uncovers the lower lateral port 35. The train-line-pipe 100 pressure also closes the valve 20 and opens the valve 16, as illustrated in Fig. 2 of the drawings. The pressure within the train-line pipe may then be reduced to any desired extent. The closing of the upper lateral passage 33 retains the pressure within the space 105 above the diaphragm 30, and the pressure beneath the diaphragm is exhausted or reduced through the communication established between the whistle-signal valve and the train-line pipe at the lower lateral port. This will 110 result in the whistle-signal valve remaining closed, so that the whistle will not blow while the brakes are being applied. When the engineer's brake-valve is put on lap, the valve 9 115 will be returned to the position shown in Fig. 3 by means of a coiled spring 36^a, disposed on the lower portion of the valve-stem 8 and interposed between a projecting head or portion 37 and a guide 38. The guide, which is pro- 120

vided with a central opening to receive the valve-stem, consists of a spider having a rim which is threaded into the lower end of the valve-casing. Also in recharging the train-line pipe the air entering the upper end of the train-line-whistle reducing-valve casing will close the check-valve of the exhaust-passage 11 and move the piston downward and uncover the feed-passage 10.

It will be seen that the train-line-whistle reducing-valve is exceedingly simple and inexpensive in construction, that while it is peculiarly adapted for freight-trains, where there is only a train-line pipe, it is also susceptible of advantageous use on passenger-trains, as it will obviate the necessity of employing a separate signal-line, and thereby greatly reduce the cost of such equipment.

Having thus fully described my invention, what I claim as new, and desire to secure by Letters Patent, is—

1. In an apparatus of the class described, the combination with an engineer's brake-valve, a train-line pipe, and a whistle-signal valve having a diaphragm, of a train-line-whistle reducing-valve interposed between the engineer's brake-valve and the train-line pipe and connected with the whistle-signal valve above and below the diaphragm thereof, said whistle-reducing valve being provided with means for reducing the pressure above the diaphragm of the whistle-signal valve when there is a reduction of pressure in the train-line pipe.

2. In an apparatus of the class described, the combination with an engineer's brake-valve, a train-line pipe, and a whistle-signal valve having a diaphragm, of a train-line-whistle reducing-valve interposed between the engineer's brake-valve and the train-line pipe and connected with the whistle-signal valve above and below the diaphragm thereof, said whistle-reducing valve being provided with means for exhausting the pressure beneath the diaphragm of the whistle-signal valve when there is a reduction of pressure by the engineer's brake-valve.

3. In an apparatus of the class described, the combination with an engineer's brake-valve, a train-line pipe, and a whistle-signal valve, of a train-line-whistle reducing-valve interposed between the engineer's brake-valve and the train-line pipe and having upper and lower ports communicating with the whistle-signal valve above and below the diaphragm thereof, said valve being provided with means for alternately opening and closing the said ports and for normally maintaining the upper port open, and the lower port closed, whereby,

when there is a reduction of pressure in the train-line pipe, the pressure will be reduced above the said diaphragm, and when there is a reduction by the engineer's valve, the upper port will be closed, and the lower port opened to reduce the pressure below the diaphragm.

4. In an apparatus of the class described, a train-line-whistle reducing-valve designed to be interposed between the engineer's brake-valve and a train-line pipe, and comprising a valve-casing having a cylinder and provided with upper and lower ports designed to communicate with a whistle-signal valve, said valve-casing being also provided with exhaust and feed passages, a piston operating within the cylinder and adapted to be automatically operated by train-line-pipe pressure and the pressure of the air from the engineer's brake-valve, and a main valve carried by the piston and provided with means for alternately opening and closing the said ports. 70

5. In an apparatus of the class described, a train-line-whistle reducing-valve designed to be interposed between an engineer's brake-valve and a train-line pipe, and comprising a valve-casing having a cylinder and provided with feed and exhaust passages, said valve-casing being also provided with upper and lower ports designed to communicate with the whistle-signal valve above and below the diaphragm thereof, a piston operating within the cylinder, and a valve carried by the piston and normally covering the lower port and having a passage extending through the valve and communicating with the upper port, said piston being adapted to be moved upward by 95 train-line pressure to open the lower port and close the upper port when there is a reduction above the piston by the engineer's brake-valve.

6. In an apparatus of the class described, a train-line-whistle reducing-valve designed to be interposed between an engineer's brake-valve, and a train-line pipe, and comprising a valve-casing having a cylinder and provided with feed and exhaust passages communicating at their ends with the cylinder, said casing being also provided with upper and lower ports adapted to communicate with a whistle-signal valve above and below the diaphragm thereof, a piston operating in the cylinder between the ends of the said passages and arranged to cover and uncover the inlet end of the feed-passage, reversely-operating valves located at the said passages, and a main valve carried by the piston and normally covering the lower port and having a passage extending through it and normally communicating with the upper port, said piston normally located between the ends of the feed-passage and movable upward when there is a reduction of pressure above it, whereby the feed-passage and the upper port will be closed and the lower port opened. 110

7. In an apparatus of the class described, a train-line-whistle reducing-valve designed to be interposed between an engineer's brake-valve and a train-line pipe, and comprising a valve-casing having a cylinder and provided with feed and exhaust passages communicating at their ends with the cylinder, said cas- 125

- 4
- ing being also provided with upper and lower ports adapted to communicate with a whistle-signal valve above and below the diaphragm thereof, a piston operating in the cylinder between the ends of the said passages and arranged to cover and uncover the inlet end of the feed-passage, reversely-operating valves located at the said passages, a main valve carried by the piston and normally covering the lower port and having a passage extending through it and normally communicating with the upper port, and a spring for returning the valve to its normal position when moved therefrom by train-line pressure.
- 15 8. In an apparatus of the class described, a train-line-whistle reducing-valve designed to be interposed between an engineer's brake-valve and a train-line pipe, and comprising a valve-casing having a cylinder provided with upper and lower ports and having feed and exhaust passages communicating at their upper ends with the cylinder at different points, and at their lower ends with the cylinder at the same point, reversely-operating spring-actuated check-valves arranged at the opposite ends of the feed and exhaust passages, a piston, and a main valve carried by the piston and normally closing the said lower port and having a passage extending through it

and consisting of lateral and longitudinal portions, the lateral portion being arranged to be carried into and out of register with the upper port and being normally in communication therewith.

9. In an apparatus of the class described, a train-line-whistle reducing-valve designed to be interposed between the engineer's brake-valve and the train-line pipe and comprising a valve-casing having a cylinder and provided with upper and lower ports designed to communicate with a whistle-signal valve, a piston operating within the cylinder and adapted to be automatically actuated by train-line-pipe pressure and the pressure of the air from the engineer's brake-valve, a main valve having a slot to receive the piston and provided with means for alternately opening and closing the said ports, and guiding means mounted on the casing and extending into the slot of the main valve.

In testimony that I claim the foregoing as my own I have hereto affixed my signature in the presence of two witnesses.

ARTHUR MARRS.
